Application December 7, 1946, Serial No. 714,838

5 Claims. (Cl. 81—3.46)

1

This invention relates to bottle openers of that type specially adapted for use with crown caps or seals.

One object of the invention is to provide an improved opener which does not distort or injure the cap in removing the same, thus enabling the cap to be restored to the bottle neck and still preserve an effective seal against escape of liquid or gas, as in the case of carbonated beverages.

Still another object is to improve the cap removing parts by the provision of a support adapted to rest upon the bottle neck, and possibly also a portion of the cap, and thus provide firm and stationary pivotal support for the cap removing lever, which thus is enabled to perform its function without damage to the cap.

Another object is to provide an improved arrangement in which the cap removing lever is pivoted about a transverse axis above the lower edge of the cap skirt so that in operation the hook portion of the lever, engaged under the edge of the cap skirt, moves upwardly and outwardly, instead of inwardly toward the central axis of the bottle neck, thus avoiding any chance of breaking or splintering the glass neck.

Another object is to provide an improved bottle opener in which the cap engaging and removing lever arm has been reduced to minimum length and consequently operates with increased power multiplication, and which opener nevertheless is of simple form, may be made and sold at low cost, and which is not likely to get out of order in service.

Further objects of the invention in part are apparent and in part will appear more in detail hereinafter.

In the drawings.

Fig. 1 represents a plan view of one embodiment of the invention;

Fig. 2 is a side elevation;

Fig. 3 is a bottom plan view, the handle being omitted;

Fig. 4 is a cross section on the line 4—4, Fig. 2;

Fig. 5 is a side elevation, illustrating the application of the opener to a capped bottle neck;

Fig. 6 is a similar view showing the opener fully applied;

Fig. 7 is a sectional plan view on the line 7—7, Fig. 6;

Fig. 8 is a sectional elevation, on the line 8—8, Fig. 7, showing the cap partly removed;

Fig. 9 is a side elevation, showing the cap fully released from the bottle neck;

Figs. 10 and 11 are views corresponding to Figs. 2 and 3, and showing another form; and

2

Fig. 12 is a longitudinal sectional elevation, showing a modification.

The bottle opener shown in Figs. 1 to 9 inclusive includes two members hinged together, to wit, a body member 10 and a supporting member 11. Both may be made from fairly strong or heavy gauge sheet metal, and are so shown, although that is not essential.

The body 10 consists of an elongated plate or strip bent into transversely arched or shallow channel form in cross section, as shown at 12 in Fig. 4, to increase its resistance to bending, and provided near one end with two depending ears or lugs 13 bent downwardly out of the plane of the sheet into parallelism with each other. Beyond said lugs the side edges 14 of the body converge along curved lines 15 to a third depending ear or lug 16, narrower than the body, and also bent downwardly, and terminating in a hook flange or claw 17 extending back, parallel to the general plane of the body, but spaced therefrom at a level below the lower ends of the side lugs or ears 13.

The supporting member 11 is in the form of a tubular ring or annulus, slightly flattened or elliptical in shape, so that it has one axis longer than the other, said member having two oppositely disposed upstanding ears 18, one at each end of the longer axis, which mate with the body lugs 13 for connection thereto by pivot or hinge pins or loose rivets, thus hinging the two parts together on a generally horizontal axis, transverse to the length of the handle and below the same, but above the level of claw 17. At the exposed or front end of the tool, ring 11 has a portion 20 bent outwardly into U form which embraces or surrounds the lug 16 and provides a space or passage 21 between the supporting ring and the bottle neck 22 through which the lug 16 works during operation of the tool, as will later appear.

This same U-shaped extension 20 of the ring provides it with two bearing points 23, one on each side of lug 16, which ride on the bottle neck and assist in locating the support and holding it firmly.

Opposite said extension, and hence beneath the handle, ring 11 is provided on its upper edge with a lug 24 extending upwardly and forwardly or inwardly toward the center of the ring, and which lug forms a foot engaging the outer portion of the cap or seal 25 near the base of the crimped flange or wall 26 thereof, and consequently at a point directly opposite a portion of the glass of

the bottle neck, where pressure by the foot 24 cannot dent or deform the metal of the cap.

Operation

To remove the cap from a bottle, the opener is applied with its parts in the relative positions shown in Fig. 2, i. e., with supporting member 11 tilted so that claw 17 extends down through the recess 21. Holding the tool in the hand, in the inclined position shown in Fig. 5, it is moved down to the position shown in Fig. 6, the claw 17 being hooked beneath the edge of the crimped flange of the cap before foot 24 is permitted to fully seat on the cap. This operation brings the supporting member 11 to a position in which it is firmly based upon the bottle and cap, with three point support tending to prevent lateral tilt or twist of the parts. Thus the support 11 now supplies a firm fulcrum, at the horizontal axis through pivot pins 19, about which the body member 10 may be swung or turned, as a lever of the first class, the short arm of the lever having a length equal to approximately the radius of the cap and the longer arm being seven to ten or more times that length. Depression of the handle now prys off the cap by movement of the claw first to engage the cap flange, as in Fig. 6, and then upwardly and outwardly to pry it loose, as in Figs. 8 and 9. The loose cap comes away with the tool, being housed or confined within the ring, and is readily grasped and returned by the same hand which operates the tool. At the same time the cap is not deformed or injured, being merely stretched slightly to pass the bulge of the bottle rim, so that it may be snapped back to place to again seal the bottle against loss of remaining content, either liquid or gas. By restoring the supporting ring to its former position, the device is again ready for another operation.

Figs. 10 and 11 show another arrangement, exactly like that before described, excepting only in its inclusion of a suitable means for always biasing the supporting ring toward the position shown in Fig. 10, ready for application to a capped bottle. The means shown for the purpose is a leaf spring 30 secured to the under surface of the handle and bearing downwardly upon foot 24. But such means may be of any desired form and is not always essential.

Fig. 12 shows still another arrangement, differing from the form shown in Fig. 2 only in that the lever in Fig. 2 is a lever of the first class while that in Fig. 12 is a lever of the second class. In other words the depending lug 16 on the body member lies between the pivots 19 and the handle end, and the claw 17 is bent forwardly instead of rearwardly and engages the near instead of the far edge or flange of the cap. Also foot 24 is on the outer, instead of on the inner, portion of the supporting ring.

This tool is applied to the capped bottle in the same manner described, but of course while tilted or inclined downwardly toward instead of away from the operator, and the cap is removed by lifting up on the handle instead of bearing down upon it.

In all forms the tool is very powerful and may be operated with minimum effort; it removes the cap without bending or distorting it; and, finally, it is durable and not likely to get out of order.

Other advantages of the invention will be apparent to those skilled in the art.

What I claim is:

1. A device for removing crown caps from glass bottles, comprising a supporting member in the

form of an annulus adapted to embrace the crimped flange of the bottle cap and to rest at one point upon the bulge of the bottle neck below said flange and at an opposite point provided with a foot adapted to rest upon the rim of the cap above the bottle neck, and a lever member pivoted upon the supporting member and having a depending claw member in substantially diametrically opposed relationship relative to the foot of said supporting member adapted for engagement beneath the edge of the cap flange for prying the cap loose upon operation of said lever.

2. A device for removing crown caps from glass bottles, comprising a supporting member in the form of an annulus adapted to embrace the crimped flange of the bottle cap and to rest at one point upon the bulge of the bottle neck below said flange and at an opposite point provided with a foot adapted to rest upon the rim of the cap above the bottle neck, and a lever member pivoted upon the supporting member on a transverse axis intermediate said two points and having a depending claw member adapted for engagement beneath the edge of the cap flange for prying the cap loose upon the operation of said lever, the claw member of said lever member and the foot of said supporting member being disposed on opposite sides of the pivotal axis of said lever.

3. A device for removing crown caps from glass bottles, comprising a supporting member in the form of an annulus adapted to embrace the crimped flange of the bottle cap and to rest at one point upon the bulge of the bottle neck below said flange and at an opposite point provided with a foot adapted to rest upon the rim of the cap above the bottle neck, and a lever member pivoted upon the supporting member and having a depending claw member in substantially diametrically opposed relationship relative to the foot of said supporting member adapted for engagement beneath the edge of the cap flange for prying the cap loose upon operation of said lever, said annular supporting member having an outwardly extending U-shaped portion in the path of travel of said claw member and providing a recess through which said claw member extends and travels.

4. A device for removing crown caps from glass bottles, comprising a supporting member in the form of an annulus adapted to embrace the crimped flange of the bottle cap and to rest at one point upon the bulge of the bottle neck below said flange and at an opposite point provided with a foot adapted to rest upon the rim of the cap above the bottle neck, and a lever member pivoted upon the supporting member on a transverse axis intermediate said two points and having a depending claw member adapted for engagement beneath the edge of the cap flange for prying the cap loose upon the operation of said lever, the claw member of said lever member and the foot of said supporting member being disposed on opposite sides of the pivotal axis of said lever, said annular supporting member having an outwardly extending U-shaped portion in the path of travel of said claw member and providing a recess through which said claw member extends and travels.

5. A device for removing crown caps from glass bottles, comprising a supporting member in the form of an annulus adapted to embrace the crimped flange of the bottle cap and to rest at one point upon the bulge of the bottle neck below said flange and at an opposite point provided with a foot adapted to rest upon the rim of the

cap above the bottle neck, and a lever member pivoted upon the supporting member on a transverse axis lying intermediate said two points and at a level above the lower edge of the cap flange and having a depending claw member adapted for engagement beneath the edge of the cap flange for prying the cap loose upon operation of said lever, the claw member of said lever member and the foot of said supporting member being disposed on opposite sides of the pivotal axis of said lever, said annular supporting member having an outwardly extending U-shaped portion in the path of travel of said claw mem-

ber and providing a recess through which said claw member extends and travels.
